UNITED STATES PATENT OFFICE.

ARTHUR T. MACE, OF EAST CLEVELAND, OHIO.

SEWING-MACHINE.

1,130,309.

Specification of Letters Patent. Patented Mar. 2, 1915.

Application filed March 30, 1914. Serial No. 828,148.

To all whom it may concern:

Be it known that I, ARTHUR T. MACE, a citizen of the United States, residing at East Cleveland, in the county of Cuyahoga and State of Ohio, have invented a certain new and useful Improvement in Sewing-Machines, of which the following is a full, clear, and exact description, reference being had to the accompanying drawings.

10 This invention relates to improvements in sewing machines, especially motor driven sewing machines, and has particular reference to a mechanism, including a motor, for incorporation in the heads of sewing machines for operatively connecting and driving the upper, or needle bar operating shafts and the shuttle actuating means thereof.

15 In motor driven sewing machines which have been used heretofore, and with which I am familiar, the motor is supported from some part of the machine and drives it through connection with the hand wheel, the usual belt, or through special gearing between the motor shaft and the needle bar operating shaft of the machine. In such constructions, the motor is usually mounted upon the table of the sewing machine where it is in the way of the operator and where it occupies space which could be advantageously utilized for other purposes. This arrangement, moreover, cannot be very conveniently incorporated in sewing machines of the "drop head" type, because, even if the head were dropped below the table of 25 the machine, the motor would still occupy its usual position, and little advantage would be accomplished by dropping the head. Efforts have been made to overcome this difficulty by locating the motor beneath the table of the machine, but this places the motor in an inconvenient position to be reached for the purpose of cleaning, oiling, or inspecting the motor. The motor has also been supported from the rear of the sewing 30 machine head, and connected through gearing to the needle bar operating shaft, which arrangement allows it to be dropped with the head of the machine. These constructions, however, leave the motor unprotected 35 from dust, lint, or ravelings and, in most cases, cause the machine to present an unsightly appearance.

40 It is the objects of my invention to provide a sewing machine which is capable of being operated, when desired, by the usual foot treadle; and to incorporate in the

mechanism that is contained within the head of the machine and operatively connects the needle bar operating device and shuttle actuated means, a motor, whereby the machine 45 may be operated through said mechanism. By this arrangement, the machine is rendered neat and attractive in appearance, and, in the preferred embodiments of my invention, the presence of the motor within the 50 head of the machine does not interfere, in the slightest degree, with the operation of the machine by the foot treadle mechanism.

More generally stated, my invention provides a machine which is equipped with the 55 usual foot treadle mechanism, and which has a motor concealed within the head of the machine, either of which may be used to drive the machine entirely independent of the other; for, as will be brought out hereinafter, means are provided whereby the foot treadle mechanism may be disconnected or thrown out of operation when it is desired to drive the machine by motor power; and, because of the ratchet connection 60 between the motor and the operating mechanism of the machine, the motor is automatically disconnected from said operating mechanism when the foot treadle mechanism is being used for running the machine.

A further object is to provide means whereby the operator may very easily and accurately control the machine, which means, when moved in one direction, acts to start the machine, and which, when moved in the 65 reverse direction, will act to retard or stop the operation of the machine.

Other objects embraced by my invention will become apparent as this description proceeds.

Generally speaking my invention may be defined as consisting of the combinations of elements set forth in the annexed claims and illustrated in the accompanying drawings forming a part hereof, wherein—

Figure 1 is a front elevation of the head of a sewing machine embodying my invention, a portion of the head of the machine being shown in central vertical section to clearly reveal the mechanism therein; Figs. 100 2, 3 and 4 are horizontal sections on the correspondingly numbered lines of Fig. 1, each of the views representing the parts as they would appear if looking in the direction indicated by the arrows associated with its 105 respective section line; Fig. 5 is a fragmentary end elevation of the head of the sewing

machine shown in Fig. 1, including a part of the means for controlling the operation of the machine; Fig. 6 is a front elevation, partly in section, of a sewing machine head embodying a modified form of my invention; Fig. 7 is a horizontal section on the line 7—7 of Fig. 6; Fig. 8 is a fragmentary, sectional front elevation of another modified form of my invention; and Fig. 9 is a horizontal section on the line 9—9 of Fig. 8, looking up.

For the purpose of illustrating my invention, I have shown it associated with a sewing machine of a well known make, which 15 comprises, generally, a bed plate 1, a head 2 which rises from one end thereof, and an arm 3 which extends horizontally from the upper end of the head, over and parallel to the bed plate 1. Extending longitudinally 20 through the arm 3, and journaled therein in the usual manner, is a needle bar operating shaft 4. This shaft may be turned by the hand wheel 5 that is secured to its end, or it may be rotated by a belt which passes 25 over a pulley 6, mounted upon the shaft alongside the hand wheel, the belt being driven by the foot treadle operated mechanism that is always present in sewing machines of this kind. A spring plunger is 30 used for locking the pulley to the hand wheel when it is desired to drive the machine by the belt, but as this is common in the art, it is thought unnecessary to illustrate it. Below the bed plate 1 there is journaled, in 35 suitable brackets 7 and 8, a shaft 9 through which the shuttle of the machine is actuated.

All of the above mentioned parts are common to sewing machines of the character herein illustrated, and, since the needle bar 40 operating mechanism that is housed within the outer end of the arm, and the shuttle actuating means, form no part of my invention, it is deemed unnecessary to include further details of these parts in the drawings, 45 than appear in such elevations as have been selected for the purpose of showing the general relation between these parts, and the mechanism which constitutes my invention.

While I have shown a shaft for operating 50 the shuttle actuating means, I wish it to be understood that I do not confine myself to the combination of my improved mechanism, with a machine having a rotating shaft for this purpose, as it is obvious that 55 the adaptation of my motor driven mechanism to a machine having various forms of shuttle actuating means, falls clearly within the scope of my invention.

As will be seen clearly from the various 60 views of the drawings, the head 2 of the machine is hollow, and situated within the lower portion of the hollow head 2 is an electric motor which is shown generally at 65 and which comprises the usual armature 11, field magnets 12, commutator 13, and

brushes 14. The armature 11 is provided with a tubular shaft 15.

I will first describe that form of my invention which is shown in Figs. 1 to 5 inclusive.

Depending from one side of the lower 70 part of the head 2 of the machine, and extending toward the vertical center of the head, is a bracket 16 which terminates in a hollow boss 17, within which is journaled the lower end of a shaft 18 that extends upwardly through the hollow shaft 15 of the armature. At its upper end the shaft is journaled within the bracket 19 that extends from one side of the head 2, and above the bracket 19, a bevel pinion 20 is pinned to 80 said shaft. This pinion meshes with a similar pinion 21 that is secured to the shaft 4 of the machine. The lower end of the shaft 18 has pinned to it a bevel pinion 22 which meshes with a bevel pinion 23 that is fixed 85 to the adjacent end of the shaft 9. For convenience of expression, the shafts 4 and 9 will be referred to as the upper and lower shafts, respectively, according to their location in the machine. From the arrangement 90 of parts thus far set forth, it will be seen that the lower shaft 9 may be operated directly from the upper shaft 4, through the shaft 18 and the gearing 20 to 23 inclusive, which allows the machine to be operated in 95 the usual manner, through the foot treadle mechanism and the belt which passes over the pulley 5; it being understood that the shaft 18 is loose within the armature shaft 15. A halved bearing 24 is provided for 100 the lower end of the armature shaft 15, which bearing forms a part of the bracket 16.

In the above form of my invention, I drive the shaft 18 from the armature shaft 15 through planetary gearing, the connection between the planetary gearing and the shaft 18 being accomplished through a roller ratchet. By this means the shaft 18 is permitted to rotate freely when the machine is 110 not running, but which will be picked up and rotated by the motor, when the motor is set in operation.

The planetary gearing includes a spur gear 25 that is keyed to the upper end of the 115 armature shaft 15, and which meshes with a pair of idlers 26 that are journaled upon pins 27 carried by a disk 28, the hub 29 whereof is loosely mounted upon the armature shaft 15. The idlers 26 mesh with an 120 internal gear 30 that is loosely journaled upon the shaft 18, said gear 30 having a hollow, annular boss 31 which rises from its upper surface and which is concentric to the shaft 18. The inner wall of the boss 31 has 125 a series of recesses 32 which contain rollers 33. A barrel 34 occupies the space within the hollow boss 31, and is fixed to the shaft 18 by a pin 35, the barrel 34 having a flange 36 which extends out over the boss 31 for 130

the purpose of retaining the rollers 33 within the recesses 32, and for protecting the parts from dust or dirt. It will be clearly seen from Fig. 2 that the recesses 32 taper from end to end, and at the larger end they are somewhat deeper than the diameter of the rollers 33; while at their reduced ends they are not as deep. This provides a roller clutch of the usual form. From this it will be seen that when the internal gear 30 is rotated in the direction indicated by the arrow in Fig. 2, the rollers 33 will be wedged between the opposed surface of the barrel 34 and the walls of the recesses 32, and will lock the parts together to drive the shaft 18 in the same direction, which is the appropriate direction to operate the machine. It is obvious from this, also, that if the shaft 18 were rotated in the direction indicated by the arrow in said Fig. 2, while the gear 30 is at rest, the rollers 33 will occupy the large ends of the notches 32 and not interfere with such rotation of the shaft.

It will be observed from Figs. 1 to 5, that a band 37 encircles the disk 28 and is retained in position by a peripheral flange 38 that projects from the lower edge of the disk. A bracket 39 is secured to the side of the head 2, and carries a stud 40 whereon is journaled a lever 41. The lever is forked adjacent the stud 40, and to the exposed portion of the stud is attached one end of the band 37. The opposite end of the band is attached to a rivet 42 that extends across the forked portion of the lever 41; and the free end of the lever 41 projects out through a slot 43 in the side of the machine head. An L-shaped lever 44 is pivoted on a stud 45 which projects from the head of the machine directly above the slot 43, and the lower end of the vertical arm of the lever is bifurcated to embrace the free end of the former lever 41. The outer end of the horizontal arm of the L-shaped lever has attached to it the upper end of a rod 46 which extends down through the bed plate of the machine where it may be connected, by a chain or other suitable means, to a foot actuated device; it being deemed unnecessary to include details of such device, as it forms no part of my invention.

A spring actuated brake is provided for the hand wheel by an angle lever 47 that is pivoted to the side of the machine head at 48. The horizontal arm of the lever extends beneath the hand wheel and carries a shoe of friction material for engaging said wheel, and is moved into contact with the wheel by a spring 49 which is anchored at one end to the machine head, and is attached, at its other end, to the lower end of the vertical arm of the angle lever. The rod 46 extends through the outer end of the horizontal arm of the lever, and depresses said lever, when it is drawn downward by

the engagement of its collar 46^a with said arm.

From this description it will be seen that when the rod 46 is drawn downward by the actuation of the foot operated device, previously mentioned, the brake will be released from the hand wheel and the L-shaped lever 44 will be rocked to move the lever 41 in a direction to draw the band 37 about the disk 28 and hold the disk against rotation. A spring 44^a, (see Fig. 5) which is attached at one end to the vertical arm of the lever 44, and at the other to a part of the machine head, tends to swing the lever 44, and consequently the lever 41, in a direction to loosen the band 37 from the disk 28.

When it is desired to drive this form of my invention by motor, the pulley 6 may be unlocked from the hand wheel 5 and the current turned into the motor. This sets the motor in operation to rotate the gear 25 that is carried by the upper end of the armature shaft 15; but with the brake applied to the hand wheel and the band 37 released from the disk 28, the rotation of the gear 25 will be wholly spent in the idlers 26, which will race about the internal gear 30, and spin the disk 28. To start the machine, the operator draws downwardly on the rod 46 which swings the L-shaped lever 44 and consequently the lever 41 in a direction to draw the band 37 about the disk 28. Gradually as the disk 28 is brought to a stop, the internal gear 30 will pick up the rotation of the motor shaft and transmit it, through the roller ratchet, to the shaft 18, and thence through to the bevel pinions 20, 21, 22 and 23 to the upper and lower shafts 4 and 9 of the machine. To stop the machine, the rod 46 is released to allow the spring 49 to apply the brake to the hand wheel and release the band 37 from the disk 28.

In the form of my invention illustrated in Figs. 6, 7, 8 and 9 I employ the same parts 1 up to 24, as are shown in connection with the form just described, and in describing the modification shown in said figures, it is thought unnecessary to repeat the description of the structure which involves these parts. The same parts will be indicated in these figures, therefore, by similar reference characters.

In the form shown in Figs. 6 and 7, I drive the shaft 18 from the armature shaft 15 through reduction gearing comprising the spur gear 50 that is keyed to the upper end of the shaft 15; a gear 51, which meshes with the gear 50 and which is journaled upon a stud 52 that is carried by a bracket 53, extending from the side of the head 2; and pinion 54 that is formed integral with the gear 51, and which meshes with a gear 55 that is loosely mounted upon the shaft 18. The gear 55 has a hub 56, which is provided with a clutch face 57, wherewith is adapted

to coöperate the corresponding face of a collar 58 that is splined to the shaft 18, and is moved toward the hub 56, by a spring 59. This provides a ratchet connection that allows the shaft 18 to be rotated independently of the motor, but which will cause said shaft to be rotated by the motor, when the same is set in operation. Because of the positive connection, through the aforesaid, between the armature shaft and the shaft 18, when the parts are being driven by the motor, I find it necessary to open the circuit which supplies current to the motor, when it is desired to stop the machine. For this purpose I provide a form of switch which will now be described. Within a hollow boss 60 which extends from the side of the head 2 beneath the hand wheel 5, is contained a sleeve 61 of insulating material within which is set a pair of metallic contact rings 62 and 63, and adapted to reciprocate within this sleeve, is a plug 64 which is forced outwardly by a comparatively strong spring 65, one end of the spring being contained within a recess formed in the inner end of the plug 64. A metallic band 66 surrounds the plug and is adapted to bridge the contact rings 62 and 63 when the plug is pressed inwardly. The rings 62 and 63 form the two sides of a break in the circuit which supplies current to the motor 10 so that when the plug 64 is pressed inwardly to connect the two rings, the circuit through the motor will be completed. Pivoted between a pair of ears 68 that extend from the side of the head 2 above the boss 60, is one end of an L-shaped lever 69 that extends beneath the hand wheel 5 and has a vertical branch that projects down alongside and engages the outer end of the plug 64. Just below the hand wheel 5, the arm is fitted with a shoe 70 of friction material for coöperation with said wheel, and the dimensions of the parts are such that, when the shoe 70 is in engagement with the wheel 5, the lower end of the vertical arm of the lever permits the plug 64 to be forced to the outer end of the sleeve 61 where its band 66 is in contact with only the ring 63. A rod 71 (similar to the rod 46 described in connection with my previous form of mechanism) is attached to the projection 72 of the arm 69, whereby the arm may be rocked upon its pivot, against the tension of the spring 65, to disengage the shoe 70 from the wheel 5, and to close the aforesaid electric switch. The operation of this form of my invention is obvious.

In the form shown in Figs. 8 and 9, the upper end of the armature shaft 15 has keyed to it a grooved pulley 73, and a larger grooved pulley 74 is loosely mounted upon the shaft 18 and is adapted to be connected therewith through the roller clutch 75, when rotated in an appropriate direction. A belt 76, which passes about the pulley 73, is

guided over a pair of idlers 77 to the pulley 74. The idlers are carried on the ends of a cross head 78 that has a threaded extension 79 which is supported within a sleeve 80 that extends from the side of the head 2 of the machine, and the extension 79 is adapted to receive a wing nut 81 for the purpose of adjusting the extension within the sleeve. Therefore, when it is desired to vary the tension of the belt 76, it is only necessary to adjust the nut 81. If the reduction in speed secured through the difference in the sizes of the pulleys 73 and 74, is insufficient, a further reduction may be accomplished through the loosening of the belt 76 and permitting said belt to slip. For the purpose of automatically taking up slack which results from the belt stretching, I insert a spring 81^a between the nut 81 and the adjacent surface of the head 2.

In all forms of my invention, it is necessary to have an opening in the rear of the machine head for the purpose of installing and removing the motor and other parts of the mechanism, and this opening is closed by a plate 90, which may be secured in place in any suitable manner, and which has openings 91 for the purpose of ventilating the motor.

Having thus described my invention, what I claim is:

1. In a sewing machine having a hollow head, an upper shaft and a lower shaft, the combination of an electric motor located within the head and having a hollow, vertically disposed armature shaft, a shaft which extends through the armature shaft of the motor and operatively connects the upper and lower shafts of the sewing machine, and a driving connection between the armature shaft of the motor and the shaft which extends therethrough, which connection is of such nature as will allow the latter shaft to be rotated in one direction independently of the former shaft.

2. In a sewing machine having a hollow head, an upper shaft and a lower shaft, the combination of an electric motor located within the head and having a hollow, vertically disposed armature shaft, a shaft which extends through the armature shaft of the motor and operatively connects the upper and lower shafts of the sewing machine, and a ratchet connection between the armature shaft of the motor and the shaft which extends therethrough.

3. In a sewing machine having a hollow head, an upper, and a lower shaft, the combination of an electric motor located within the head of the sewing machine and having a hollow, vertically disposed armature shaft, a shaft which extends through the armature shaft and operatively connects the upper and lower shafts of the sewing machine, a pulley secured to the armature shaft, a second

5 pulley loosely mounted upon the shaft which passes through the armature shaft, ratchet connection between the second pulley and the shaft upon which it is mounted, a pair of idlers, and a belt which passes over the first mentioned pulley, the idlers and the second mentioned pulley.

10 4. In a sewing machine having a hollow head, an upper, and a lower shaft, the combination of an electric motor located within the head of the sewing machine and having a hollow, vertically disposed armature shaft, a shaft which extends through the armature shaft and operatively connects the upper 15 and lower shafts of the sewing machine, a pulley secured to the armature shaft, a second pulley loosely mounted upon the shaft which passes through the armature shaft, ratchet connection between the second pulley 20 and the shaft upon which it is mounted, a member movable toward and from the pulleys, a pair of idlers carried by said member, a belt which passes over the first mentioned pulley, the idlers and the second mentioned 25 pulley, and a means tending to move the aforesaid member away from the pulleys.

30 5. In a sewing machine having a hollow head, an upper shaft and a lower shaft, the combination of an electric motor located within the head of the sewing machine and having a hollow, vertically disposed armature shaft, a shaft which extends through the armature shaft and operatively connects the upper and lower shafts of the sewing 35 machine, a pulley secured to the armature shaft, a second pulley loosely mounted upon the shaft which passes through the armature shaft, ratchet connection between the second pulley and the shaft upon which it is mounted, a belt through which the second pulley is 40 driven from the first pulley, guides for said belt, and means whereby the tension of said belt may be varied.

45 6. In a sewing machine having a hollow head, an upper shaft, and a lower shaft, the combination of an electric motor located within the head of the sewing machine and having a hollow, vertically disposed armature shaft, a shaft which extends through the

50 armature shaft and operatively connects the upper and lower shafts of the sewing machine, a pulley secured to the armature shaft, a second pulley loosely mounted upon the shaft which passes through the armature shaft, ratchet connection between the second 55 pulley and the shaft upon which it is mounted, a belt whereby the second pulley is driven from the first pulley, idlers over which the pulley is driven, a cross head at each end of which is carried one of the 60 idlers, and means for adjusting the position of the cross head with respect to the aforesaid pulleys.

65 7. In a sewing machine having a hollow head, an upper shaft and a lower shaft, the combination of an electric motor located within the head and having a hollow, vertically disposed armature shaft, a shaft which extends through the armature shaft of the motor and operatively connects the upper 70 and lower shafts of the sewing machine, a pulley secured to the armature shaft, a second pulley upon the shaft which passes through the armature shaft, a pair of guides, and a belt which passes over the first mentioned pulley, the guides and the second 75 mentioned pulley.

8. The combination, with the needle bar operating device and the shuttle actuating means of a sewing machine, of an electric 80 motor located within the head of the machine and having a hollow, vertically disposed armature shaft, a shaft which extends through the armature shaft of the motor and operatively connects the aforesaid needle bar 85 operating device and the shuttle actuating means, and a driving connection between the armature shaft of the motor and the shaft which extends therethrough, which connection is of such nature as will allow the latter 90 shaft to be rotated in one direction independently of the former shaft.

In testimony whereof, I hereunto affix my signature in the presence of two witnesses.

ARTHUR T. MACE.
